UNITED STATES PATENT OFFICE.

CARL R. KLOK, OF CHICAGO, ILLINOIS, ASSIGNOR, BY MESNE ASSIGNMENTS, TO UNITED TABLE-BED COMPANY, A CORPORATION OF VIRGINIA.

FOLDING BED.

1,244,988.

Specification of Letters Patent.

Patented Oct. 30, 1917.

Application filed May 26, 1913, Serial No. 769,890.

Renewed September 17, 1917. Serial No. 191,893.

To all whom it may concern:

Be it known that I, CARL R. KLOK, a citizen of the United States of America, and resident of Chicago, Cook county, Illinois, have invented a certain new and useful Improvement in Folding Beds, of which the following is a specification.

My invention relates to folding beds in general, but more particularly to combination beds—that is to say, beds which are combined with other articles of furniture, and especially table beds.

Generally stated, the object of my invention is to provide a novel and highly efficient folding bed.

A special object is to provide a folding bed which, when folded, will swing horizontally about a vertical pivot or axis, whereby the unfolding of the bed, when used with a table, for example, does not necessitate the removal of the table top, the latter being left undisturbed.

It is also an object to provide certain details and features of construction tending to increase the general efficiency, desirability and convenience of a table bed of this particular character.

To these and other useful ends, my invention consists in matters herein disclosed and claimed.

In the accompanying drawings, Figure 1, is a plan of the table body and bed frame of a folding table bed embodying the principles of my invention, showing the said table body in horizontal section, and showing the folding bed frame broken away between the ends thereof for convenience of illustration.

Fig. 2, is a section on line 2—2 in Fig. 1.
40 Fig. 3, is a vertical section on line 3—3 in Fig. 4.

Fig. 4, is a vertical section on line 4—4 in Fig. 5.

Fig. 5, is a horizontal section on line 5—5 in Fig. 4.

Fig. 6, is an enlarged detail section on line 6—6 in Fig. 1.

Fig. 7, is an enlarged detail section on line 7—7 in Fig. 1.

50 As thus illustrated my invention comprises a table A provided with vertical end walls a, disposed at two corners thereof, and a back wall a¹, said walls being all rigidly connected together by the upper and lower

walls a² and a³ of the table top. In this way 55 a hollow or box-like table top is provided with a rectangular chamber a⁴, the said table top being provided at the four corners thereof with legs a⁵ which are rigidly secured thereto; and it will be observed that the two 60 walls a extend downward to form part of two of said legs.

The rectangular bed frame B is composed of three sections, the end sections b and b¹ being U-shaped and the middle section b² 65 being composed of two straight lengths of angle iron. The said sections b and b² are jointed or hinged together by means of short links b³, and the sections b² and b¹ are similarly connected together by means of 70 links b⁴, whereby said bed frame, when folded or rolled up, provides sufficient space therein for the mattress b⁵, as shown more clearly in Fig. 4. It will be understood that the said folding bed frame, which is preferably composed of angle iron, has a suitable fabric stretched thereon to support said mattress. Folding legs b⁶ are pivoted at opposite sides of the section b², and have their upper ends connected by bars or links b⁷ 80 with the links b³ of the frame. Similar legs b⁸ have their upper end portions pivoted upon the sides of the frame section b¹, and the upper ends of these legs are connected by bars or links b⁹ with the frame links b⁴, 85 in the manner shown more clearly in Fig. 2. With this arrangement, the legs b⁶ and b⁸ automatically fold up in the manner shown in Fig. 4, when the bed frame is folded and reduced to a compact bundle for disposition 90 within the chamber a⁴ of the table top. The end section b of the bed frame is provided with rigid side walls b¹⁰ and b¹¹ and with a rigid end wall b¹²; and in addition the wall b¹¹ is provided with rigid legs b¹³, similar 95 to those of the table, which rest on the floor immediately outside of the legs a⁵ of the table. The vertical walls a and b¹² are hinged together at b¹⁴, whereby the entire bed swings upon a vertical axis at one corner thereof, which is at one corner of the table, when the bed is moved in or out of the table. In other words, the table and bed 100 are operated together for relative swinging movement about a vertical axis. The wall b¹⁰ has a similar wall b¹⁵ hinged to the end thereof, the combined length of these two walls being sufficient to close the opening in

- the side of the table top; and it will also be seen that the hinge b^{16} thereof is of such character that the two walls fold at right angles to each other, when the bed is swung around and pushed into the table. The purpose of the wall b^5 is to completely close the opening in the side of the table top, and support the upper wall a^2 thereof, when the bed is in use.
- 10 As a matter of further and special improvement, in connection with a bed of this particular character, the vertical walls b^{10} and b^{11} are provided with brackets C, which are provided with pins c, and the angle iron 15 of the bed frame section b is provided with notches c¹ which engage the said pins, in a suitable manner, whereby the bed frame can be lifted away or detached from the walls b^{10} , b^{11} , and b^{12} , if for any purpose this becomes desirable. The outward swing of the bed about the pivot b^{14} , the upper and lower ends of which extend into the walls a^2 and a^3 , (see Fig. 6,) can be limited in any suitable manner, as by a pin b^{17} that travels in 20 a curved slot b^{18} in the upper surface of the bottom wall a^3 of the table, the end of the slot serving as a stop for said pin; and the friction between the inner surfaces of the walls a^2 and a^3 and the upper and lower 25 edges of the wall b^{15} can be utilized for causing the wall b^{15} to straighten out or assume a position in alinement with the wall b^{10} , when the bed is pulled out.

From the foregoing it will be seen that 30 by my invention I provide a table bed of such character that the bed, when folded, is in compact form within the table top. The structure meets all of the standard requirements regarding height—that is to say, 35 the top of the table is the right height for working purposes, as, for example, writing and other similar kinds of work; the bed is the right height when unfolded, and is neither too high nor too low, as was very 40 often the case in structures of this kind, owing to the fact that certain requirements in a combination of this kind were obtained at the expense of sacrificing others; and in 45 my improved table bed, as herein shown and described, it is also true that sufficient clearance is insured below the wall a^2 , without having the bed too high, whereby the structure is suitable for use as a library table, and may be used with all of the convenience 50 of an ordinary table by the average adult seated in an ordinary chair in front thereof. Thus, notwithstanding the combination character of the structure, the table and bed are of such character that each is perfectly 55 adapted for its own particular purpose without interfering in any way with the standard requirements of the other.

60 Thus the invention is adapted to solve some of the various problems involved in 65 the combining of a table with a folding bed

frame of this particular character, in one unitary structure, so that the result will be a satisfactory article of furniture for both purposes, but the invention is not, of course, limited to the exact construction shown and 70 described.

What I claim as my invention is:—

1. A folding bed comprising a body frame, an auxiliary frame pivoted in said body frame, adapted to swing outward 75 about a vertical axis, and a folding spring bed bottom carried by said auxiliary frame and comprising pivotally connected sections one of which is mounted permanently right-side-up thereon. 80

2. A folding bed comprising a body frame, an auxiliary frame pivoted in said body frame, adapted to swing outward about a vertical axis, and a folding spring bed bottom carried by said auxiliary frame and 85 comprising pivotally connected sections one of which is mounted permanently right-side-up thereon, said auxiliary frame having legs for supporting one end of the bed.

3. A folding bed comprising a body 90 frame, an auxiliary frame pivoted in said body frame, adapted to swing outward about a vertical axis, and a folding spring bed bottom carried by said auxiliary frame, said body frame having a table top below which 95 the auxiliary frame and bed bottom are concealed, the bed being adapted to be unfolded without disturbing said table top.

4. A folding bed comprising a body frame, an auxiliary frame pivoted in said 100 body frame, adapted to swing outward about a vertical axis, and a folding spring bed bottom carried by said auxiliary frame, said bed bottom having one end thereof fixed in said auxiliary frame, and provided 105 with folding legs for supporting the other end thereof in position for use.

5. A folding bed comprising a rectangular body frame, a rectangular auxiliary frame pivoted in said body frame, 110 adapted to swing outward about a vertical axis, and a folding spring bed bottom carried by said auxiliary frame, said axis being located at one corner of the auxiliary frame, and said auxiliary frame being adapted to 115 stand at right angles to said body when the bed is in use.

6. In combination, a body, and a folding bed in said body, said bed and body being pivoted together for relative movement 120 about a vertical axis, preliminary to unfolding of the bed, and said bed comprising a transversely folding frame whereof one section is supported permanently right-side-up 125 from the floor.

7. In combination, a table forming a body, and a folding bed in said body, said bed and body being pivoted together for relative movement about a vertical axis, preliminary to unfolding of the bed, and said 130

table having a fixed top which remains right side up during folding and unfolding of the bed.

8. In combination, a body, and a folding bed in said body, said bed and body being pivoted together for relative movement about a vertical axis, preliminary to unfolding of the bed, and said bed comprising a transversely folding frame whereof one section is supported permanently right-side-up a fixed height from the floor, said body and bed being pivotally connected at their corners.

9. In combination, a body, and a folding bed in said body, said bed and body being pivoted together for relative movement about a vertical axis, preliminary to unfolding of the bed, said bed including a frame composed of pivotally connected links and sections, said links providing space for the bedding when the bed is folded, and each link being parallel with said axis when the bed is folded.

10. In combination, a body, and a folding bed in said body, said bed and body being pivoted together for relative movement

about a vertical axis, preliminary to unfolding of the bed, and said bed comprising a transversely folding frame whereof one section is supported permanently right-side-up a fixed height from the floor, said bed having means to close the body when folded therein.

11. In combination, a body, and a folding bed in said body, said bed and body being pivoted together for relative movement about a vertical axis, preliminary to unfolding of the bed, said bed having both fixed and foldable legs.

12. In combination, a body, and a folding bed having a three-section frame in said body, said bed and body being pivoted together for relative movement about a vertical axis, preliminary to unfolding of the bed, the third section of the bed frame having said axis at one corner thereof and being permanently right-side-up, as set forth.

Signed by me this 19th day of May, 1913.

CARL R. KLOK.
